TOOTHBRUSH POWER HANDLE OR SIMILAR ARTICLE

Carl N. Johnson, Stratford, Conn., assignor to General
Electric Company, a corporation of New York

Filed Aug. 11, 1967, Ser. No. 3,238

Term of patent 14 years

(Cl. D4—15)

Fig. 1.

Fig. 2.

Fig. 3.

Fig. 4.

Fig. 5.

FIG. 1 is a front perspective view of a toothbrush power handle embodying my new design;

FIG. 2 is a top plan view thereof;

FIG. 3 is a front elevational view thereof;

FIG. 4 is a left side elevational view thereof; and

FIG. 5 is a right side elevational view thereof.

The dominant features of my design reside in the portions shown in full lines.

I claim:

The ornamental design for a toothbrush power handle or similar article, substantially as shown and described.
